United States Patent Office

Des. 183,613
Patented Sept. 30, 1958

183,613

INFLATABLE BUILDING

Kenneth E. Joy, Vienna, Va.

Application February 21, 1958, Serial No. 49,757

Term of patent 14 years

(Cl. D13—1)

(Granted under Title 35, U. S. Code (1952), sec. 266)

Fig. 2.

Fig. 3.

Fig. 1 is a perspective view of an inflatable building showing my new design;

Fig. 2 is a plan view of the same building; and

Fig. 3 is a front elevational view.

The essential features of my design reside in the portions shown in full lines.

I claim:

The ornamental design for an inflatable building, as shown and described.
